UNITED STATES PATENT OFFICE.

ALBERT E. NEWTON, OF WORCESTER, MASSACHUSETTS.

GEARING.

No. 895,103.

Specification of Letters Patent.

Patented Aug. 4, 1908.

Application filed July 7, 1903. Serial No. 164,570.

To all whom it may concern:

Be it known that I, ALBERT E. NEWTON, a citizen of the United States, residing at Worcester, in the county of Worcester and State of Massachusetts, have invented a new and useful Gearing, of which the following is a specification.

The object of this invention is to improve the construction of drilling machines especially upright drilling machines the invention especially relating to a construction by which the gearing used for driving and feeding the drill spindle can be conveniently arranged and accurately and economically manufactured.

Referring to the accompanying two sheets of drawings forming part of this application for patent, Figure 1 is a side elevation of an upright drilling machine with a preferred embodiment of my invention applied thereto. Fig. 2 is a plan view illustrating the centers of the gearing between the drill spindle and feeding mechanism, and Fig. 3 is a sectional view taken on the planes 3-3 of Fig. 2.

Referring to the drawings, and in detail, A designates the framing; B and B' tight and loose pulleys; C the driving cone pulley, and D the driven cone pulley.

A belt is arranged between the cone pulleys C and D and by this construction, which is a usual one, power is applied to the machine. The cone pulley D is loosely mounted on a horizontal shaft 10 loosely journaled in brackets at the top of the frame work. Turning with said cone pulley D is a pinion 11 which has clutch teeth on its face. A sliding clutch 12 is keyed on said shaft 10. A shaft 13 is journaled in a bearing in the framing below the shaft 10 and carries a gear 14 of a size proper to mesh with the pinion 11 and a pinion 15 of a size proper to mesh with a gear 16 secured on said shaft. A handle 17 is pivoted to the main framing and has two arms, one engaging a groove on the sliding clutch 12 and the other a groove on the hub of the gear 14. By this construction, power can be taken directly through the shaft 10 by locking the sliding clutch into the clutch teeth on pinion 11; or can be taken down through the shaft 13, which constitutes a back gear shaft, by sliding the clutch 12 out of mesh with the pinion 11, the gear 14 to mesh with the pinion 11 and the pinion 15 to mesh with the gear 16. This operation or the opposite one to re-mesh the clutch and

disconnect the back gearing is done by a single movement of the handle 17.

A bevel pinion 18 is mounted on the end of the shaft 10 and meshes with a bevel gear 19 secured on the end of a hub journaled in the bearing at the end of the drill frame. A drill spindle 20 is provided with a key-way and engages a key secured in the hub of said bevel gear 19 in the usual manner. The drill spindle passes through and is journaled in the usual quill 21. This quill is fitted in the drill head E adjustably mounted on ways formed on the drill frame.

T designates the usual work supporting table which is mounted on the column of the drill frame.

The quill 21 is provided with the usual rack 22, engaging which is a pinion mounted on the end of a shaft controlled by the handles 23. A worm-shaft is journaled in the drill head E and carries a worm 24 which meshes with a worm-wheel 25. A friction clutch 26 is arranged on the face of said worm-wheel 25. A hand-wheel 27 is secured on the end of the worm-shaft. A bevel gear 28 is loosely journaled on the other end of the worm-shaft and a clutch 29 is provided so that said bevel gear 28 can be connected with, or disconnected from, the worm shaft. The bevel gear 28 is driven by a bevel pinion 30 secured on the end of a feed rod 31.

The foregoing mechanism comprises a drilling machine in which the power can be applied directly or through back gearing, in which the drill spindle can be moved quickly up or down by means of the handles 23, in which the drill spindle can be moved up or down accurately by means of the hand-wheel 27, or in which drill spindle can be fed by power through the bevel pinion 30, bevel gear 28, clutch 29 worm 24, and the worm-wheel 25 transmitting power through the friction clutch 26 to the pinion meshing with the rack 22.

The foregoing mechanism constitutes some of the parts of a drilling machine of an improved style of manufacture. In making this drilling machine, it is necessary that some direct, simple form of change gearing shall be provided to turn the feed rod 31 at various speeds for different feeds. Difficulty has been encountered in providing a change gearing which shall serve these functions, which can be economically manufactured and quickly put in place. To overcome this

difficulty, I have provided the following mechanism which constitutes the improvement forming the subject matter of this application for patent. On the end of the bevel gear 19 and below its bearing is secured a gear 32 from which power is taken to actuate the feed rod 31. The change speed gearing for taking power from this gear to the feed rod is constructed as follows: 33 designates a bracket which is provided with two integrally formed hubs 34 and 35. Inside of the hub 34 is fitted a bushing 36. A key is inserted in this bushing and the same is bored out to fit the feed rod 31 which has a key way cut therein. Four gears 37, 38, 39 and 40 are secured on said bushing 36. Said bushing 36 is held in place by means of suitable collars 41. Journaled in the other hub 35 of the bracket 33 is a hollow shaft 42 loosely fitted on which are four gears 43, 44, 45 and 46 meshing with the gears 37, 38, 39 and 40 previously referred to. This system is proportioned to get the desired adjustment of feed. The gears 43 to 46 have key-ways cut in their hubs. Sliding in said shaft 42 is a shaft 47, fitted in which is a spring-pressed pivoted key 48, which extends out through a slot cut in the hollow shaft 42 to engage the key-ways cut in any one of the gears 43 to 46. Pins are arranged in said slot in said hollow shaft, so that said key will properly pass from one gear to the next. Said shaft 47 is provided with a handle or button 49 by which the same can be actuated. By this construction, by sliding the shaft 47 up or down, power can be taken through any one of the series of the four intermeshing gears. Secured on the end of the hollow shaft 42 is a gear 50. The upper end of the hub 35 is turned off concentrically with the shaft 42 so as to leave a collar 51. Fitted on the said concentric hub 52 thus formed is a swinging bracket 53. A collar 54 is usually provided on the hollow shaft 42 between said concentric hub 52 and the gear 43. A shaft 55 is journaled in a bearing 56 formed at the end of the swinging bracket 53 and is provided with a collar 57 to keep the same in place. A gear 58 is secured to the end of said shaft 55 and is meshed with the gear 50 secured on the end of the hollow shaft. Another gear 59 is secured on the end of the said shaft or to said gear 58. This gear 59 is considerably larger than the gear 58 and is designed to mesh with the gear 32 on the hub of the driving bevel gear 19.

This construction can be readily assembled and put together on the bench. When it is desired to apply this change speed gearing to the drill the bracket 33 is secured in place on the drill frame so that the feed rod 31 will properly line with the bushing 36. Then the bracket 53 is turned on the concentric hub 52 until the gear 59 properly meshes 65 with the gear 32. The hub of the swinging

bracket 53 which fits on the concentric hub 52 is preferably split and a clamping screw 60 is provided so that said swinging bracket can be held in adjustable position. An ear is also provided on said swinging bracket 53 so that a pin 61 can be additionally used to lock the swinging bracket 53 in its adjustable position on the bracket 33 if desired. Thus this gearing can be quickly and accurately applied in place on the drill frame and can be 70 manufactured and assembled in large quantities and quickly put in place on the machines as they are set up.

By the construction described, four changes of feed can be obtained, but it is obvious that 80 this number can be increased or decreased as desired.

I am aware that other changes may be made in the construction by a skilled mechanic and that features of the invention 85 may be applied to other mechanism than drilling machines and to other types of drilling machines than the one shown in the drawings without departing from the scope 90 of my invention as described in the claims.

Having thus fully described my invention what I claim and desire to secure by Letters Patent is:

1. In an upright drilling machine, a bracket, a change speed gearing carried above said bracket, an adjustable bracket mounted on the first bracket, and a gear carried by the second bracket below the first bracket for driving said change speed gearing arranged so that the same can be adjusted or 100 swung without destroying the mesh of the gearing, whereby said bracket can be secured to the drill-frame, and the adjustable bracket set to mesh the gear to the gear which is to drive the same.

2. In an upright drilling machine, the combination of a bracket having two integrally formed hubs, a feed rod supported by one of said hubs, a shaft supported solely by the other of said hubs, a change speed gearing arranged between said shafts and comprising a gear on the end of the shaft, a swinging bracket concentrically mounted on one of said hubs, gearing carried by said swinging bracket and meshing with the gear 115 on the shaft, and means for locking this bracket in adjusted position.

3. In an upright drill, the combination of a bracket having two integrally formed hubs, a bushing in one of said hubs, a feed rod slideable through said bushing and arranged to turn therewith, a series of gears arranged between said hubs, and connected with the bushing, a swinging bracket mounted on one of said hubs, means carried by said swinging bracket for transmitting power to the series of gears, and means for locking the swinging bracket in adjusted position.

4. In an upright drilling machine, the combination of a feed-rod, a bracket having 130

two hubs, a bushing journaled in one of said hubs into which the feed rod slides, a series of gears secured to said bushing, a hollow shaft journaled in the other hub, a series of 5 gears intermeshing with the first series loosely mounted on said hollow shaft for connecting any one of said gears to said hollow shaft, a swinging bracket mounted concentrically on said hub, a gear mounted on 10 the end of said hollow shaft, a shaft journaled in the end of said swinging bracket, a gear mounted thereon meshing with the gear on the end of the hollow shaft and another gear mounted thereon for connecting to the 15 gear which is to actuate the change speed gearing.

5. In an upright drilling machine, the combination of a bracket having two hubs, a bushing journaled in one of said hubs and

adapted to receive a feed rod, a series of 20 gears secured to said bushing, a shaft journaled in the other hub, a series of gears intermeshing with the first series loosely mounted on the shaft for connecting any one of said gears to said shaft, a swinging bracket 25 mounted concentrically on said hub, a gear mounted on said shaft, a shaft journaled on said swinging bracket, and a gear mounted thereon meshing with the gear on the end of the shaft.

In testimony whereof I have hereunto set my hand, in the presence of two subscribing witnesses.

ALBERT E. NEWTON.
